UNITED STATES PATENT OFFICE.

WILLIAM J. HOSCEIT, OF CHICAGO, ILLINOIS, ASSIGNOR TO NATIONAL DUMP CAR COMPANY, OF CHICAGO, ILLINOIS, A CORPORATION OF MAINE.

DOOR-OPERATING MECHANISM.

1,388,950.

Specification of Letters Patent. Patented Aug. 30, 1921.

Application filed December 26, 1919. Serial No. 347,372.

To all whom it may concern:

Be it known that I, WILLIAM J. HOSCEIT, a citizen of the United States, residing at Chicago, in the county of Cook and State of Illinois, have invented certain new and useful Improvements in Door-Operating Mechanism, of which the following is a specification.

This invention relates to door operating mechanism, particularly in connection with 10 general service cars.

The objects of the invention are to provide a simple and efficient door operating mechanism which is positive in its action and so 15 arranged that no strain is placed upon the mechanism tending to distort it, thus minimizing repairs; to provide a device which can be easily operated by the class of lever usually employed for such purpose; and to 20 provide an operating device so arranged as to increase the efficiency of the car in unloading.

These and other objects are accomplished by means of the arrangement disclosed on 25 the accompanying sheets of drawings, in which—

Figure 1 is a fragmentary side elevation of 30 a general service car embodying my invention;

Fig. 2 is a transverse sectional view of the same taken in the plane of line 2—2 of Fig. 1;

Fig. 3 is a detail sectional view on an enlarged scale showing the door operating 35 mechanism in one of its positions; and

Figs. 4 and 5 are detail sectional views, parts being shown in elevation, and taken in the planes of lines 4—4 and 5—5 of Fig. 2.

The various novel features of the invention 40 will be apparent from the following description and the drawings, and will be particularly pointed out in the appended claims.

This invention is an improvement on the 45 arrangement disclosed in the Hart Patent No. 1,318,444, granted October 14, 1919, and in view of the fact that many advantages are common to the door operating mechanism disclosed therein and in my present arrangement, only the particular improvements claimed herein will be particularly described.

I have chosen to illustrate my invention in connection with a general service car having sides 10, ends 11, and a floor composed

largely of dump doors 12 which are pivotally connected at their inner ends to the center sill structure 13, the framework of the car including transverse supporting and strengthening members 14 which are provided with stop members 15, upon which the dump doors 12 rest in an open position.

This invention has to do primarily with a door operating mechanism. Having in mind the disadvantages of door operating devices heretofore employed and the advantages of the present door operating mechanism, attention is called to the fact that each of the dump doors is raised from an open position to a closed position separately and 60 independently of any other one of the doors.

Slidably secured to the bottom of each one of the doors, at the outer edge and preferably midway the length of the same, is a latch 16 having a downwardly projecting 70 finger 17, the function of which will be referred to later.

As shown in full lines at the right-hand side of Fig. 2, the dump door 12 is in its lower or open position. Under such conditions an operating shaft 18, which is laterally and bodily movable in a plurality of slots 19 in the transverse frame members 14, occupies its outermost position. With the shaft 18 in its outermost position, each of the dump doors 12 may be raised individually and directly by hand by inserting any suitable stake 20 into a receiving socket 21 carried on the under side of each of the doors.

With the latch in its inward, non-functioning position, the doors 12 may be raised into closed position, whereupon the latch will be moved outwardly into a position where it rests upon and is supported by the shaft 18 with the latter in its outermost position. Accordingly, the door 12 is supported in its raised or closed position by the operating shaft through the sliding latch 16. This supporting arrangement, however, is a temporary one, but as soon as all of the dump doors have been raised into closed position and their slidably mounted latches have been moved outwardly by hand to rest upon the associated shaft, as indicated in Fig. 3, the shaft may be moved laterally inwardly to a position under the doors for permanently supporting the latter. During the inward movement of the shaft 18, it engages the dependent fingers 17 on the latches 16, caus-

ing the latches to be moved inwardly at least to a point where the outer edges of the latches are flush with the outer edges of the dump doors 12, as shown at the left-hand side of Fig. 2. It is apparent that after the shaft is now moved outwardly beyond the outer edges of the dump doors, the latter are free to drop into an open position for dumping purposes. It is seen, therefore, 10 that the dump doors are raised directly and independently by hand and are temporarily held in closed position by the shaft through the overlying latches, the load later being transferred permanently to the shafts when 15 the shafts are moved inwardly under the doors, at which time the latches also are moved inwardly into a non-latching position, the shafts in their innermost positions under the doors forming a permanent supporting 20 arrangement. When the shaft in any section of the car is moved outwardly, all of the doors in that particular section of the car supported by the associated shaft are dropped simultaneously.

25 The slots 19 as here shown extend slightly inwardly and upwardly from the sides of the car, so that the doors 12 are given their final closing movements as the shafts are moved inwardly. In this particular case I 30 have provided means to make the operation of the shafts positive in a manner to meet the various requirements under service conditions. This means includes arms 22 which are fixed on and turn with the shafts, it being understood that each shaft preferably has at least two such arms spaced thereon. Pivotaly connected to the free end of each of said arms is one end of a link 23, while the other end of which in each case is connected preferably to any stationary part of the car, such as the frame member 14. From 35 this arrangement it is apparent that when the shaft, as shown at the right-hand side of Fig. 2, is rotated in a counterclockwise direction, it will be moved toward the left through the slot 19 in a positive manner until it reaches its inward limit of movement, as shown at the left-hand side of Fig. 2. The arm 22 and its link 23 in each case in 40 such position lie in a straight line forming a secondary lock; the primary lock, of course, being the usual ratchet and pawl mechanism 24 at the end of each shaft. As said shafts are moved inwardly under the doors they 45 shift the latches 16 inwardly and give to the doors their final closing positions in which the doors 12 are supported. To permit the dump doors 12 to open, the shaft, as shown at the left-hand side of Fig. 2, is rotated 50 in a counterclockwise direction, whereupon, through the linkage connection, it will be moved toward the left through the slot 19 in a positive manner, the shaft being arrested in its other limit of movement at the 55 outer end of the slot, as shown, for ex-

ample, at the right-hand side of Fig. 2. During an inward movement of the shaft, it will be understood that the free end of the link 23 is depressed a certain amount and then rises into the straight line position with 70 respect to its associated arm to form the secondary lock for the shaft. This extreme or locked position of the shaft is broken by a rotation of the shaft in the proper direction, whereupon the free end of the link 23 75 in each case is lowered a certain predetermined amount and then is raised slightly as the shaft reaches its outer limit of movement. By using this door operating mechanism not only is the use of chains obviated, 80 but also it is unnecessary to provide the shafts with gear members and also it is unnecessary to provide a stationary part of the car with racks to mesh with the shaft gears during the operation of the doors. 85

It is my intention to cover all modifications of the invention falling within the spirit and scope of the following claims.

I claim:

1. In a general service car having a plurality of doors, means for directly raising said doors individually, and means including a door control shaft having a supporting and a non-supporting position with respect to an associated door and a pivotally mounted link for locking one of said doors in raised position. 90

2. In a general service car having a plurality of doors, means for directly actuating said doors individually in a given direction, and means including an operating shaft having a supporting and a non-supporting position with respect to an associated door and a pivotally mounted link operatively connected to the shaft for holding one 100 of said doors in a given position.

3. In a general service car having a plurality of doors, means for directly lifting said doors individually, means including a shaft for temporarily holding said doors in 110 raised position, and means including a link operatively connected to said shaft for permanently holding said doors in raised position.

4. In a general service car having a door, 115 a shaft, hand operated means carried by the door for engaging said shaft for temporarily supporting the door in a given position, a link one end of which is anchored, and an arm carried by the shaft and connected to the 120 link whereby when the shaft is rotated in one direction it will be moved positively in a lateral direction under the door for permanently supporting the latter.

5. In a general service car having a door, 125 a shaft, means whereby said door may be temporarily held in raised position by said shaft, and means including a pivotally mounted link anchored at one point and operatively connected to said shaft whereby 130

the latter may be moved positively into a position for permanently supporting the door in raised position.

6. In a general service car having a door, a shaft, a transverse frame member having a slot in which said shaft is laterally moveable, means whereby the door may be temporarily held in raised position by said shaft, an arm rotatable with said shaft, and a link connected to said arm and anchored at one point whereby when the shaft is rotated it will be moved positively laterally in said slot to permanently support the door in raised position.

7. In a general service car having a door, a laterally movable shaft, means whereby said door may be temporarily held in raised position by said shaft, an arm rigid with said shaft, and a link pivotally connected to said arm and anchored at one point whereby when the shaft is rotated the latter will be moved positively in a lateral direction to permanently support the door in raised position.

Signed at Chicago, Illinois, this 19th day 25 of December, 1919.

WILLIAM J. HOSCEIT.
